(No Model.)

H. P. FEISTER.

ROTARY PAPER AND CARD CUTTING MACHINE.

No. 247,817.

Patented Oct. 4, 1881.

UNITED STATES PATENT OFFICE.

HENRY P. FEISTER, OF PHILADELPHIA, PENNSYLVANIA.

ROTARY PAPER AND CARD CUTTING MACHINE.

SPECIFICATION forming part of Letters Patent No. 247,817, dated October 4, 1881.

Application filed January 27, 1881. (No model.)

To all whom it may concern:

Be it known that I, HENRY P. FEISTER, a citizen of the United States, residing in the city and county of Philadelphia, and State of Pennsylvania, have invented a new and useful Improvement in Rotary Paper and Card Cutting Machines, of which the following is a specification.

My invention relates to an improvement in that class of rotary paper and card cutting machines in which gangs of circular cutting or shearing knives are placed adjustably on parallel rotating shafts, (one above the other,) the edges of the upper knives being placed in close proximity to and slightly overlapping the edges of the knives on the lower shaft, and then made to rotate toward each other, in a cutting or shearing manner, by twin gears secured to the ends of the parallel shafts, the paper being first fed into parallel feed-rolls in front and carried into the circular cutting-knives, and carried through them into similar and like speeded rolls in the rear of the cutting-knives, (called "delivery-rolls,") and cut into long parallel strips, (called "slittings,") after which these parallel strips are reversed and again passed through the knives "crosswise," and cut into business or other cards suitable for market.

The accompanying drawings fully set forth my improvement, in which Figure 1 is a side elevation and part-sectional view, (one housing or side frame being removed to better illustrate the internal working parts;) Fig. 2, a part-sectional view of the mechanism used to actuate the feeding-fingers, the view showing it as seen from the front of the machine; Fig. 3, a perspective view of my card-receiving racks detached from their trough. Fig. 4 shows the trough detached from the machine, with front side removed and the card-receiving racks in position, together with cards assembled in one of the spaces, illustrating the manner in which they are delivered by the machine.

Similar letters refer to similar parts throughout the several views.

The shafts B and C, fitted with circular cutting-knives D D, are made to rotate in the housings A A in the direction shown by the arrows. Feed-rolls E E and delivery-rolls F F revolve in the same direction, the velocity of their peripheries being made equal to that of the cutting-edges of rotating knives D D.

The apron or table G is provided with slots

H, corresponding with feed-fingers L' L' L' L', in which the feed-fingers L' reciprocate, the fingers projecting slightly above the table G, in order to carry forward the strip W into feed-rolls E E. The feed-guide I extends entirely across the table G, parallel with feed-rolls E E, and is slotted transversely at i, corresponding to slots H in table G, the fingers L', on their return motion, passing into slots i and remaining there while the strip W (to be cross-cut into cards) is being placed in front of them and against guide I, to be then carried forward into feed-rolls E E.

W' is the pack of strips (or slittings) to be cross-cut into cards; W², the strip being carried into feed-rolls E E; W⁴, the cards cut and delivered "home" into the receiving-racks R, W⁴, Fig. 4, also showing the manner in which the cut cards are assembled or stacked in the receiving-racks R as they emerge from delivery-rolls F F.

On the under side of feed-table G are bolted, parallel to each other, grooved guides J J, the grooves facing each other, and the guides set at right angles to feed-rolls E E. To these grooves are fitted semicircular tongued and slotted arcs K K, the arcs K K being secured together by stay-rods k k k. On top of arcs K K are arranged adjustable finger-rod carriers L L, having longitudinal V-shaped slots y extending nearly their entire length, thus admitting the finger-bar g to be adjusted to suit various widths of strips in cross-cutting by simply loosening the thumb-screws M, which pass through an extension of the tongue on arcs K K and engage with the nut y², and moving the finger-rod carriers L L to the desired position and again fastening thumb-screw M.

p p and p' p' are hangers bolted to grooved guides J J and to arms of housings A' A', and in which crank-shafts P P rotate, motion being transmitted thereto from cutter-shaft C by belts P² and pulleys on crank-shafts P P.

The roller-shaft O is fitted with friction-rollers N N, one on each end, and is secured to and rotates with cranks O' O', and imparting reciprocating motion to arcs K K, which carry finger-rod g.

For receiving the cut cards as they pass from the delivery-rolls F F, I use the devices shown in Figs. 3 and 4, also shown in position in rear of machine, Fig. 1. These I call "delivery-racks," not "boxes," as those used heretofore were

called. I construct them as follows: A wood or metallic trough is made of a length suitable for the number of racks I may desire to use. This trough consists of bottom Q and parallel side 5 pieces, Q' Q', and top guide, S', the guide S' being recessed on the under side, thus forming a slot nearly its entire length to accommodate the thumb-screws S S, used for securing the tongued and slotted receiving-racks R in their 10 several positions of adjustment, depending on the widths of cards it is desired to cut.

The receiving-racks R R are made of brass or sheet metal of any kind, (or wood will answer if made very smooth and accurate.) They 15 are made in shape as shown in Fig. 3, being right-angled and provided with series of parallel tongues r and slots r', extending to within one inch of their apex, the ends of the slots terminating parallel with said apex. These 20 parallel tongues r are made to correspond with similar parallel slots, r', on the next adjoining rack R, and to interchange with and adjust with each other until as many racks are placed in the trough as it may be desired to use, they 25 being placed in the trough with the tongues downward, as shown in Fig. 4, and secured in their requisite positions by thumb-screws s, as before stated.

The top surfaces of all the racks R, when 30 placed in the trough, as shown in Fig. 4, will then stand at an angle of forty-five degrees with each other. This will cause the cards to assemble in the racks R, as shown at W⁴, Fig. 4, with their edges in parallel vertical lines, 35 leaving spaces between each pair of packs to facilitate their removal from the racks R. When full the receiving-racks above referred to are placed as shown in Fig. 1, the apex of each rack being placed in line with each alternate pair of rotating cutting-knives D D, the apex of each rack serving to separate each alternate cut made by the cutting-blades D D as the cards drop from the delivery-rolls F F, and thus separate themselves by contact with 45 apex of racks R, thus causing two packs of cards to assemble between each pair of the racks R, as shown at W⁴, Fig. 4.

It will be seen, also, on reference to the drawings, Figs. 3 or 4, that the racks R may be adjusted to different positions in the trough Q, and to suit various widths of cut, their angles still remaining the same—viz., forty-five degrees—thus maintaining the very desirable feature of assembling the cards on the racks R 55 with their edges vertical, as shown at W⁴, Fig. 4.

On the under side of inclined table V are brackets V², and on the top are secured ratchet-plates U, provided with joints or pivots q and t and pawl T, this device being used to raise the rear side of the trough, containing racks R, to different angles, it being sometimes necessary to do so, some classes of cards having more velocity as they emerge from rolls F 65 F than others, chiefly owing to the difference in weight of the card-stock.

The operation of my invention is as follows:

A rotary motion is imparted to the crank-shafts P P by cutter-shaft C through belts P², (two being used, but only one shown,) thus giving 70 a reciprocating motion to the semicircular slotted arcs K K, by means of cranks O' O', roller-shaft O, and friction-rollers N N, rotating in the semicircular slots, the finger-bar carriers L L also partaking of the same motion by being mounted on top and moving with reciprocating arcs K K, the arcs K K being guided in their movement by grooved guides J J.

I is the feed-guide, E E the feed-rolls, L' L' 80 L' L' the feeding-fingers, and W' the pack of strips about to be cut into cards. The feeding-fingers L' are caused to remain at rest during about half a revolution of the crank-shafts P, or while they are revolving in the slotted arcs K K concentrically, the fingers remaining during this time under the guide I in slots i. This is a very desirable feature, as the temporary stoppage and rest of fingers L under guide I affords the operator ample time 90 to carefully lay and adjust the strip in front of guide I previously to its being carried forward to the feed-rolls E E by fingers L'. It also enables the machine to be run at a much greater speed than heretofore, and still give 95 ample time for properly feeding it.

My feeding mechanism also guarantees a better delivery of the cut cards into its receiving-racks R, as the more accurate the strips are carried to the feed-rolls the more 100 uniform will be the delivery of the cut cards, the rest or stoppage of the feeding-fingers under guide I always permitting the operator to carefully adjust the strip and insure its parallel entry into feed-rolls E E.

In cutting cards, the strips (or slittings) are placed on the feed-table, as at W', and then in front of the fingers L, and carried into the feed-rolls, as at W, and through the rotating knives D D and delivery-rolls F F, as at W³, 110 then delivered and assembled in receiving-racks R, as at W⁴.

Having fully described my invention, I claim as new—

1. In a rotary paper or card cutting machine, semicircular tongued and slotted arcs K K, in combination with the adjustable finger-bar carriers L L, having longitudinal V-shaped slots y y and thumb-screws M, substantially as shown and described.

2. In a rotary paper or card cutting machine, receiving-racks R, having parallel tongues r, corresponding to and interchanging or adjusting with parallel slots or recesses r' of adjoining rack, and operated in combination with trough Q, substantially as set forth and described.

3. The combination, in a rotary paper or card cutting machine, of ratchet-plates U, pawls T, pivots q and t, and trough Q, adapted to operate as set forth.

Attest: HENRY P. FEISTER.

FRANCIS ROBINSON,
JAMES S. KOCH.
